UNITED STATES PATENT OFFICE

163,211

EXPANSIBLE BRACELET

Samuel Meyerson, Brooklyn, N. Y.

Application June 14, 1950, Serial No. 10,508

Term of patent 14 years

(Cl. D45—4)

To all whom it may concern:

Be it known that I, Samuel Meyerson, a citizen of the United States, residing in Brooklyn, county of Kings, and State of New York, have invented a new, original, and ornamental Design for an Expansile Bracelet, of which the following is a specification, reference being had to the accompanying drawing forming part thereof.

Figure 1 is a top plan view of an expansile bracelet embodying my new design a portion of the center being omitted for convenience of illustration;

Figure 2 is a side elevational view of the bracelet; the conventional bottom links being shown in broken lines;

Figure 3 is a top plan view thereof with the links in expanded position;

Figure 4 is an enlarged perspective view of one of the top links;

Figure 5 is a cross sectional view taken on the line 5—5 of Fig. 4; and

Figure 6 is a transverse section on line 6—6 of Fig. 4.

The dominant feature of my design for an ex-

pansile bracelet resides in the specifically contoured top links, each link being characterized by the transverse groove across the center thereof in association with the gradual downward slope of the substantially flat top surface from this center groove toward each end.

I claim:

The ornamental design for an expansile bracelet, as shown and described.

SAMUEL MEYERSON.
